REFLEX THERMOPRINTING

Carl S. Miller, St. Paul, and Carl A. Kuhrmeyer, New Canada Township, Ramsey County, Minn., assignors to Minnesota Mining and Manufacturing Company, St. Paul, Minn., a corporation of Delaware

Application April 2, 1956, Serial No. 575,435

4 Claims. (Cl. 250—65)

This invention relates to the reproduction of printed matter or the like on heat-sensitive copying-paper by a novel method which for convenience is here termed reflex thermoprinting. The method involves the application of intense radiant energy in a direction through the copying-paper to and from the differentially reflective surface of the printed page or other graphic subject-matter of which a copy is desired, the conversion of radiant energy to heat energy within the copying-paper in an intensity pattern determined by such subject-matter, and the formation of visible copy in the copying-paper at the high-intensity areas of such pattern.

This invention is related to the invention described and claimed in the copending application of Carl S. Miller, Serial No. 747,338, filed May 10, 1947, now Patent No. 2,740,896.

The invention has particular utility in affording means for rapidly obtaining one or more copies of printed matter, diagrams, photographs, or other graphic subject-matter directly from the original, as in conducting library searches or the like. There is involved merely the proper positioning of the sensitive copy-paper with respect to the original, and the exposure of the original to intense radiant energy through the copy-paper. A true copy is produced directly, without the necessity of subsequent development of a latent image or of other processing. Both negative and positive copies are easily made.

The invention is applicable to the copying of any type of original document carrying visible copy, including painted, inked, or dyed as well as printed or typewritten originals. Messages written in inks of all colors have been copied, as have messages produced by hectographic processes and consisting of organic dyes transferred to white paper.

The attached drawing, which is not necessarily to scale, illustrates in cross-section a strip of heat-sensitive copy-paper 10 associated with a graphic original 11, e. g. a printed page, and irradiated with intense radiant energy from a suitable source 13. The copy-paper is here shown to consist of a radiation-transmissive backing or carrier member 14 and a heat-sensitive layer 15. The printed page has inked portions 16 and ink-free surface areas 17. When the lamp 13 is flashed, there is directly produced in the strip 10 a negative copy of the graphic subject-matter of the original 11; that is, the areas of the heat-sensitive layer above the ink-free portions of the surface 17 are visibly changed, as illustrated in the drawing.

The following discussion is offered in probable explanation of the effect just described. It is believed that the radiant energy coming from the source 13 is partially absorbed in the heat-sensitive layer 15, but to an extent insufficient to provide sufficient heating effect to cause a visible change. The transmitted portion of the radiant energy impinges on the surface of the original, where portions reaching the inked area 16 are absorbed while portions reaching the ink-free surface 17 are reflected.

2

The reflected energy is returned to the heat-sensitive coating 15 where a further portion is absorbed and converted to heat energy. The total amount of heat thus provided within the layer 15 raises the temperature at that point to the level required for activating and visibly altering the heat-sensitive layer. The radiation absorbed at the area 16 does not return to the heat-sensitive layer, which at the corresponding area then remains in its original condition. Any heat energy liberated in inked area 16 on absorption of the radiant energy from the lamp 13 is dissipated before it reaches the heat-sensitive layer, or is prevented from reaching the layer by the intervening backing member 14 or by other means.

High-intensity photoflash bulbs provide a useful source 15 of high-intensity radiant energy, but other sources having still higher output of radiant energy are preferred. One such source, indicated in the drawing, consists of a Pyrex glass or quartz tube about ten inches long, having an electrode at each end, filled with xenon or other inert gas under reduced pressure, and externally wound with an open wire spiral. The spiral is connected to a 20,000 volt spark coil while the electrodes of the flash tube are connected to an energy storage bank providing a potential of 2600 volts D. C. and capable of applying a 500 watt-second discharge. Activation of the tube, by closing the circuit to the spark coil, results in an intense flash having a duration of about 1000 microseconds, with peak intensity at about 100 microseconds. Intensity is high in the infra-red, and particularly high in the visible, 30 regions.

The flash source just described has been found effective in the copying of all types of graphic subject-matter on rapidly-reactive heat-sensitive copying-paper. One such copying-sheet consists essentially of a thin coating 35 on a transparent thin paper base of a fusible organic iron salt and a reactive phenol in a non-fusing organic film-forming binder. The copying-paper transmits a substantial proportion of the radiant energy and is not visibly changed when exposed to a single flash from the source described. However, the reflection of a substantial portion of the thus transmitted radiation, and the resultant additional absorption of a portion of the reflected energy, as described in connection with the drawing, develops sufficient heat energy in the heat-sensitive layer to make 45 possible the inter-reaction of the reactive components and the production of a visible change.

In one specific example, the copy-sheet consisted of thin map overlay tracing paper coated with a thin layer of a suspension of ferric stearate and gallic acid in a 50 solution of ethyl cellulose. The dry sheet was light tan in color, changing almost instantaneously to a brownish black when heated to 90–120° C. When the sheet was placed over a printed page and irradiated as previously described, with the flash lamp at a distance of ½ inch 55 from the paper, a negative copy of the printed area was obtained.

Another specific example of a suitable rapidly-reactive heat-sensitive copying-paper has a sensitive coating of a mixture of gum guaiac and cerium stearate in an ethyl cellulose binder. Brief heating of such a sheet converts the initially substantially colorless coating to a dark colored modification; further heating causes a further conversion to the colorless state. The sheet is therefore first converted uniformly to the colored modification, in which 60 form it still transmits a significant proportion of the radiation from the lamp. However on placing it against a black-on-white printed original and irradiating as described, a positive copy of the graphic markings of the original is obtained in the copy-paper in the form of dark markings on a light background.

Many other heat-sensitive copying-sheets are useful in

the practice of this invention, the two just described being given as illustrative rather than limitative examples.

The carrier web may be thin paper as already indicated, but may equally well be transparent film material, e. g. cellulose acetate or ethyl cellulose film. In any case, the carrier should be capable of transmitting substantially all of the impressed radiation. The ethyl cellulose or other binder component of the sensitive coating may itself serve as a carrier web when present in sufficient quantity, but in such cases some means of preventing direct contact between copy-sheet and original is usually found desirable. Thus the copy-sheet may be separated from the original by a thin section of silk bolting-cloth or other equivalent transparent heat barrier. The extent of such separation must be limited, however, if clear and sharp images are desired, because of excessive diffusion of radiation when the original and the heat-sensitive layer are too widely separated. With sufficiently high intensity and short duration of flash, the heat-barrier layer may be omitted.

Rapidly reactive heat-sensitive compositions are necessary for best results, particularly where the radiant energy flash is of the indicated short duration. A wide variety of reactive systems are known which are fully effective, the reactants being capable of reacting together even at normal room temperatures but being physically prevented from so reacting at below activation temperatures. Other mechanisms are also available.

The heat-sensitive layer must be partially absorptive of the radiant energy while still transmitting a substantial proportion of such energy. For example, a layer which absorbs too much of the radiation in a single pass either will be visibly changed over its entire area regardless of the surface beneath, or the amount of radiation remaining for reflection and further absorption will be inadequate to differentially convert the corresponding areas. The degree of absorption is easily and exactly controlled by the addition of various pigments or the like to the normally highly transparent heat-sensitive layer; thus, small amounts of titanium dioxide and of carbon black have both proven useful for this purpose where the copy-sheet in the absence of such materials did not form an adequately visible image due to excessive transmission of the radiant energy. Such pigments are also useful in providing increased contrast in the final copy.

Another method of increasing the absorption of image-carrying radiant energy in the heat-sensitive layer, and thus increasing the extent of visible change, involves the formation of a reflective grid over the outer surface of the layer, e. g. by printing with a silver ink. Radiation which passes through the openings of the grid and is reflected by the more reflective areas of the original is in part re-reflected by the grid into the heat-sensitive layer to increase still further the development of heat energy at such areas.

The effectiveness of the copying process depends also on the intensity of the radiant energy. For example, a copy-sheet which does not provide an effective copy with a particular source of energy may be found fully effective if the energy level is substantially increased. With increased energy, the distance between lamp and sheet may be increased, thereby permitting duplication over somewhat wider areas. Radiant energy absorbed in the absorbent printed areas of certain originals and converted to heat energy is more rapidly dissipated and prevented from affecting the image-forming layer when the radiant energy is at suitably high intensity. Lamp structures and

systems capable of providing such increased intensity are available and form no part of the present invention.

Increased area of copy is also obtainable by employing a number of flash tubes operating simultaneously, or by flashing a single tube at suitable intervals over the area involved. Reflectors and other optical components may be included to provide irradiation of maximum uniformity. Flash tubes may alternatively be provided with flattened and extended surfaces for increased uniformity of irradiation.

What is claimed is as follows:

1. A method for the production of permanent facsimile copies of a graphic original having a visible graphic pattern on a visibly contrasting background, said pattern and background being differentially reflective of intense radiant energy, said method comprising placing over the graphic original a heat-sensitive rapidly-reactive copy-paper capable of absorbing a substantial proportion of said energy, and irradiating the original through the copy-paper with said intense radiant energy at sufficiently high intensity and for sufficiently short time to provide a visible change in the areas of the copy-paper corresponding to the more reflective areas of the original while avoiding visible change in areas corresponding to the less reflective areas.

2. A method for the production of permanent facsimile copies of a graphic original having a visible graphic pattern on a visibly contrasting background, said pattern and background being differentially reflective of intense radiant energy, said method comprising: (a) placing over the graphic original a copy-paper consisting essentially of a rapidly-reactive heat-sensitive layer and an associated thin transparent carrier, said heat-sensitive layer being capable of absorbing a substantial proportion of said energy and said copy-paper being placed with the carrier web in contact with the graphic original; and (b) irradiating the original through the copy-paper with said intense radiant energy at sufficiently high intensity and for sufficiently short time to provide a visible change in the areas of the heat-sensitive layer corresponding to the more reflective areas of the original while avoiding visible change in areas corresponding to the less reflective areas.

3. A method for the production of permanent facsimile copies of a graphic original having a visible graphic pattern on a visibly contrasting background, said pattern and background being differentially reflective of intense radiant energy, said method comprising: (a) placing over the graphic original a copy-paper having a rapidly-reactive heat-sensitive layer, said heat-sensitive layer being capable of absorbing a substantial proportion of said energy and being prevented from directly contacting the graphic original by an intervening thin transparent heat-insulative fibrous sheet material; and (b) irradiating the original through the copy-paper with said intense radiant energy at sufficiently high intensity and for sufficiently short time to provide a visible change in the areas of the heat-sensitive layer corresponding to the more reflective areas of the original while avoiding visible change in areas corresponding to the less reflective areas.

4. The method of copying as defined in claim 3 in which the thin fibrous sheet material is a separate thin web.
